(57) **CLAIM**

The ornamental design for a laundry treating appliance, as shown and described.

DESCRIPTION

FIG. 1 is a top perspective view of a laundry treating appliance;

FIG. 2 is a front view of the laundry treating appliance of FIG. 1; and,

FIG. 3 is a left side view of the laundry treating appliance of FIG. 1.

The broken lines illustrate portions of the laundry treating appliance that form no part of the claimed design.

1 Claim, 3 Drawing Sheets
